CLAIM

The ornamental design for a water cooling cabinet for battery charging as shown and described.

DESCRIPTION

FIG. 1 is a perspective view of a water cooling cabinet for battery charging;

FIG. 2 is a front elevation view of the water cooling cabinet for battery charging;

FIG. 3 is a rear elevation view of the water cooling cabinet for battery charging;

FIG. 4 is a right side elevation view of the water cooling cabinet for battery charging;

FIG. 5 is a left side elevation view of the water cooling cabinet for battery charging; and,

FIG. 6 is a top plan view of the water cooling cabinet for battery charging.

The broken lines shown in the drawings are for the purpose of illustrating portions of the water cooling cabinet for battery charging that form no part of the claimed design.

1 Claim, 6 Drawing Sheets
